VALVE MECHANISM FOR GAS-RETORTS.

1,166,184.

Specification of Letters Patent. Patented Dec. 28, 1915.

Continuation of application Serial No. 780,898, filed July 24, 1913. This application filed October 29, 1914. Serial No. 869,231.

To all whom it may concern:

Be it known that I, HENRY A. CARPENTER, a citizen of the United States, residing at Sewickley, in the county of Allegheny and State of Pennsylvania, have invented certain new and useful Improvements in Valve Mechanism for Gas-Retorts, of which the following is a specification.

The present invention relates to improvements in valve mechanism for gas retorts, being a continuation in part, of that filed by me July 24, 1913, Serial Number 780,898, the present disclosure including certain additional amplifying features.

15. The general invention disclosed herein and in said parent application pertain more particularly to apparatus in which the mouth-pieces are adapted to connect with the stand-pipe, the latter serving as a conduit for a plurality of separate retorts. In practice, it is desirable that communication between the mouth-piece and stand-pipe be generally open, a closure of such communication being had when it is desirable to open 20. the mouth-piece lid for any purpose; the prior application is based more particularly on the means which are employed to prevent opening of the door prior to closing of the valve which is employed for the purpose 25. of establishing such communication; the specific valve arrangement being reserved for the present application.

As will be readily understood, the passage-way from the mouth-piece to the stand-pipe has a tendency to collect ingredients from the gas passing therethrough, and, as a result, the seat for the valve which controls the passage-way tends to clog up with consequent liability of an imperfect seating 35. of the valve, and this is especially the case where the valve itself is located directly in the path of travel of the gas to or through the passage-way.

The present invention aims to overcome 45. these objections, together with others hereinafter indicated, and has for its objects, the provision of a valve mechanism which is simple and efficient in operation, durable in construction, and which will be effective 50. in retaining the valve and its seat in condition to provide for maximum efficiency of the retort apparatus.

To these and other ends, the nature of which will be readily understood as the invention is hereinafter disclosed, said invention consists in the improved combination and construction of parts hereinafter fully described, illustrated in the drawings, and more particularly pointed out in the appended claims.

In the accompanying drawings, in which similar reference characters indicate similar parts in each of the views, Figure 1 is a view partly in plan and partly in section of a portion of a retort mouth-piece shown in connection with a stand-pipe, and provided with valve mechanism, the view showing portions of retort closure means; Fig. 2 is a detail view partly in section showing the passage-way between the mouth-piece and the stand-pipe, with the valve in position therein; Fig. 3 is a view similar to Fig. 1 showing the valve in a different position and showing additional means for holding the valve to its seat; Fig. 4 is a front elevation of parts shown in Fig. 3, and showing different positions of the valve; Fig. 5 is an end elevation looking in the direction of the arrow in Fig. 4; and Fig. 6 is a detail sectional view showing additional leakage prevention means, the section being taken on line 6—6 of Fig. 5. Figs. 1 and 2 of the drawings are disclosures of views of the above-identified application, these views disclosing the general features of the present application, these features being first described.

1 designates a mouth-piece designed to be connected with a stand-pipe 2, the latter being provided with openings 3 adapted to coöperate with outlet passages or nozzles 4 of the mouth-piece to form a passage-way from the retort to the stand-pipe. Preferably, the stand-pipe is adapted to be located between adjacent rows of mouth-pieces, the latter being connected to the stand-pipe on opposite sides. The nozzles are each provided with a seat 5 at the outlet to the passage-way, and the nozzle and stand-pipe have complementary faces adapted to engage 100 to provide for an efficient joint connection therebetween.

The communication between the mouth-piece and the stand-pipe is controlled by

means of valve mechanism which is so positioned and arranged that when the passage-way is open, the valve will be spaced therefrom, and preferably located at a point 5 out of proximity with the outlet to the passage-way, thereby tending to prevent deposits thereon sufficient to affect the seating of the valve; in addition, the valve structure is so formed as to tend to clear the seat as 10 well as the valve from such deposits during the seating movement of the valve, in order that the actual closing may provide against material leakage.

A preferred way of producing the result 15 is shown in the drawings, in which the valve stem is in the form of a bent arm 8, a portion of which is in the form of a shaft 10 projecting outwardly from the mouth-piece and having its bearing in a casing 11, the 20 outer end of the shaft 10 being preferably shaped, as at 12, to permit a tool, not shown, to be placed thereon and by means of which the shaft 10 and the arm 8 may be oscillated with the shaft as the axis of oscillation, the 25 shaft axis extending at substantial right angles to the axis of the passage-way.

As shown in Fig. 1, the inner portion of the arm is bent at an angle with the shaft, and said arm, as shown in Fig. 4, has its 30 inner end adapted to carry the valve 7 with a ball and socket joint connection, the valve 7 being preferably of the ball type. As shown in Fig. 2, this particular arrangement is such that the valve 7, in its movements toward and from its seat, describes an 35 arcuate path which places the valve, when the passage-way is open for operation, below and to one side of the passage-way the result being that while the valve itself is, with- 40 in the mouth-piece, it is positioned somewhat out of the direct path of the gas into and through the passage-way, and therefore less liable to the deposit of impurities thereon. As the valve seat, however, is located in 45 immediate proximity to such path, it is subjected to such deposits; hence, when the valve is to be closed, it is desirable to provide for eliminating these deposits as much as possible in order that the valve may be 50 seated substantially free from leakage. This action is provided by the particular movement of the valve support and the ball and socket connection of valve 7 and arm 8, this connection being in the nature of a universal 55 joint.

As will be readily understood, the valve 7 is substantially free to move on the ball 9 during travel to and from its closing position, the result being that as the valve approaches its seat, any change in position made during such movement will be corrected by contact with the seat. Such correction obviously provides a relative movement between valve and seat and thus dis- 60 lodges the impurities or otherwise destroys 65

their ability to prevent accurate fitting of valve and seat so that when the valve becomes actually seated, the joint will be substantially free from leakage. In providing this result, not only is the shape of the support important, but also the shape of the valve itself, the seating face of the latter being somewhat spherical, so that as it approaches its seat, it will practically fit thereon even though it is not accurately positioned on its support, tending to accommodate for variations in accumulations as it approaches its seating position. As the movement, however, continues, this condition is righted by a correction in the position of the valve, causing a movement of its seating face in such manner as to tend to remove accumulations by abrasion. Since the valve is loosely mounted, it will be readily understood that the liability of successive position corrections bringing precisely the same parts of the valve and seat into contact is very small, so that there is a tendency to a self-cleaning which will retain the valve seat and valve comparatively clear of the accumulations, this being especially true in connection with the use of tension means, presently described, for retaining the valve in its closed position, such tension means tending to force the position-changing effect. 70 75 80 85 90 95

As shown in Figs. 1 and 2, the shaft 10 is provided with a stop member 14 which in the general arrangement of said prior application, co-operates with the door operating mechanism to prevent movements of the latter to open the door prior to the closing of the valve 7. In the amplification of the general invention set forth herein, this member is given the additional function of positively retaining the valve in its closed position, this being provided by the use of a member 30 having the general configuration shown in Figs. 3, 4 and 5, this member being secured to the mouth-piece and having its free end located in the path of travel of the toe of the member 14, such free end being bent at a point where the toe will pass slightly beyond the bending line when the valve is seated, the result being that said member 30 will act as a retaining means for the valve to prevent accidental valve opening. The member 30 may, if desired, be formed of resilient material, thereby placing the closed valve under a tension action. 100 105 110 115 120

A further amplification is disclosed in Fig. 6, in which the shaft 10 is shown as mounted in a specially designed structure for the purpose of rendering the joint gas tight. This is provided by employing two members 31 and 31^a having opposing faces, complementary on approximately spherical lines, the member 31 being carried by a threaded tubular member 32 mounted in the mouth-piece, the member 31^a being carried 125 130

by the shaft 10. The shaft 10 extends through the tubular member and has its outer end provided with holding means which may be in the form of a sleeve 33 keyed to the shaft, or which may be the member 14 and nut 13 of the remaining figures. In either case, an annular abutment is provided at the outer end of the member 32 with which a spring 34 is adapted to contact, the opposite end of the spring contacting with an internal shoulder 32^a of the member 32, this arrangement placing the shaft 10 under tension in a direction to hold the opposing faces of the members 31 and 31^a leakage-proof, and still permit of the swinging movements of the valve through the oscillation of the shaft 10, the members 31 and 31^a practically forming a universal joint at this point.

As will be seen, the arrangement of parts disclosed herein will provide for maximum efficiency in preventing leakage, the several features coöperating in this respect. For instance, the forming of the valve semi-spherical or ball-shape and mounting it on an arm adapted to swing to and from position through an arc, with a ball and socket mounting, automatically provides for an action which will tend to eliminate the effect of the impurities deposit on the valve seat. Another effect is to locate the valve, in open position, out of the direct path of travel of the gas through the passage-way and thereby reduce the liability of the impurities depositing upon the valve itself. Furthermore, by mounting the shaft 10 with its axis extending at substantially right angles to the axis of the passage-way, the general construction is simplified and manipulation of the valve to provide the swinging movement to and from closing position rendered possible with minimum leakage and by the use of ordinary actuating means.

While I have herein shown and described a preferred form of construction, it will be readily understood that variations or modifications thereof may be required or desired to meet the various exigencies of use, and I desire to be understood as reserving the right to make any and all such changes or modifications as may be required to meet such conditions in so far as the same may fall within the spirit and scope of the invention as expressed in the accompanying claims.

What I claim is:—

1. The combination with a retort mouth-piece, of a stand-pipe in communication therewith, a seat on the mouth-piece, a ball valve operable in the mouth-piece controlling communication between the mouth-piece and stand-pipe, and valve actuating means.

2. The combination with a retort mouth-piece, of a stand-pipe in communication therewith, a seat on the mouth-piece, a ball valve operable in the mouth-piece control-

ling communication between the mouth-piece and stand-pipe, and valve actuating means including a universal joint connection.

3. In combination, a stand-pipe, a retort mouth-piece communicating therewith through a passage-way having a valve seat, and a valve mounted to swing toward and from said seat, said swinging movement being on an arc to carry the valve out of the general gas travel path to and through the passage-way.

4. In combination, a stand-pipe, a retort mouth-piece communicating therewith through a passage-way having a valve seat, and a valve mounted in said mouth-piece to swing toward and from said seat.

5. In combination, a stand-pipe, a retort mouth-piece communicating therewith through a passage-way having a valve seat, said valve being loosely supported, whereby the swinging movement may effect position changes corrected by the seating action of the valve.

6. In combination, a stand-pipe, a retort mouth-piece communicating therewith through a passage-way having a valve seat, a valve movable toward and from the seat, and supporting means for the valve adapted to permit change in position of the valve on its support under change in center of gravity, said means bringing the valve to its seat in a position to require valve position correction by the seat in closing the passage-way.

7. In combination, a stand-pipe, a retort mouth-piece communicating therewith through a passage-way having a valve seat, and valve mechanism for controlling said passage-way, said mechanism including a valve, and a support therefor comprising a shaft having its axis at substantially right angles to the axis of the passage-way, and an arm extending laterally from the shaft, the valve being positioned at the end of the arm.

8. In combination, a stand-pipe, a retort mouth-piece communicating therewith through a passage-way having a valve seat, and valve mechanism for controlling said passage-way, said mechanism including a valve, and a support therefor comprising a shaft having its axis at substantially right angles to the axis of the passage-way, and an arm extending laterally from the shaft, the valve being positioned at the end of the arm, the connection of valve and arm being in the form of a universal joint.

9. In combination, a stand-pipe, a retort mouth-piece communicating therewith through a passage-way having a valve seat, and valve mechanism for controlling said passage-way, said mechanism including a valve, and a support therefor comprising a shaft having its axis at substantially right angles to the axis of the passage-way, and

- an arm extending laterally from the shaft, the valve being positioned at the end of the arm, said shaft being located to cause the valve to swing out of the direct path of the gas to and through the passage-way.
10. In combination, a stand-pipe, a retort mouth-piece communicating therewith through a passage-way having a valve seat, and valve mechanism for controlling said passage-way, said mechanism including a valve, and a support therefor comprising a shaft having its axis at substantially right angles to the axis of the passage-way, and an arm extending laterally from the shaft, the valve being positioned at the end of the arm, a bearing for the shaft, and a spring for holding the shaft in gas-tight engagement with the bearing.
11. In combination, a stand-pipe, a retort mouth-piece communicating therewith through a passage-way having a valve seat, and a valve mounted in said mouth-piece to swing toward and from said seat, and fixedly positioned means external of the mouth-piece and in the path of movement of the valve mechanism for retaining the valve in closed position.
12. In a combination, a stand-pipe, a retort mouth-piece communicating therewith through a passage-way having a valve seat, and a valve mounted in said mouth-piece to swing toward and from said seat, and fixedly positioned means external of the mouth-piece and in the path of movement of the
- valve mechanism for yieldingly retaining 35 the valve closed.
13. In combination, a stand-pipe, a retort mouth-piece at one side of the stand-pipe and formed with a passage-way in communication therewith with a valve seat 40 for the passageway controlling such communication, a valve, and a pivotally mounted valve support for moving the valve toward and from its seat.
14. In combination, a stand-pipe, a retort mouth-piece at one side of the stand-pipe and formed with a passageway in communication therewith with a valve seat for the passageway controlling such communication, a valve, and a valve support mounted 50 to turn about a horizontal axis for moving the valve toward and from its seat.
15. In combination, a stand-pipe, a retort mouth-piece at one side of the stand-pipe and formed with a passageway in communication therewith with a valve seat for the passageway controlling such communication, a valve located within the mouth-piece, and a valve support mounted to turn about a horizontal axis located within the mouth-piece 60 for moving the valve toward and from its seat.

In testimony whereof I affix my signature in presence of two witnesses.

HENRY A. CARPENTER.
